RADIAL SEAL FOR ROTARY REGENERATIVE
HEAT EXCHANGER

Richard W. Bellows, Wellsville, N.Y., assignor, by mesne assignments, to Combustion Engineering, Inc., a stock corporation of Delaware

Filed Apr. 13, 1961, Ser. No. 102,725
2 Claims. (Cl. 165—9)

The present invention relates generally to heat exchange apparatus and particularly to an improved radial sealing arrangement for use between relatively rotatable parts of a rotary regenerative heat exchanger.

In rotary regenerative heat exchange apparatus of the type herein defined, a cylindrical rotor has compartments carrying heat transfer material which is first exposed to a stream of heating fluid and then, as the rotor is turned about its axis, the compartments of heat transfer material are exposed to air or other fluid to be heated passing through a spaced passage where the heated heat transfer material imparts absorbed heat to the air. The rotor is surrounded by a housing having end or sector plates formed with openings that provide for the flow of heating gases and air therethrough. To prevent mingling of the two fluids, radial partitions that form the rotor compartments are provided with radial sealing members adapted to wipe against the imperforate portions of the sector plate.

Conventionally a rotor for a heat exchanger assumes a dished configuration during operation due to the differential of expansion between the "hot" end that lies adjacent the inlet for the heating fluid and the "cold" end that lies adjacent the inlet for the cooler fluid to be heated. Since the radial sealing members are usually secured to the end edges of the radial partitions in such a manner that they are forced to conform to the thermal deformation of the radial partitions to which they are attached, the sealing relationship between the sealing members and the adjacent end plate is easily disturbed to permit extensive leakage of fluid therebetween.

Thus it may be seen that sealing means must be readily adaptable to varying clearance conditions if they are to serve their intended function to effectively limit the leakage of fluids between relatively movable surfaces. Motivated by this information, radial sealing means have been mounted independent from the radial partitions or else they have been pivoted to the partitions in order that they might be biased into a sealing arrangement with the confronting surface of an adjacent end plate. Such an arrangement of sealing means has been found to have much merit in that the sealing relationship between relatively movable members is held substantially constant throughout a wide range of distortion of the rotor and its surrounding housing.

Attempts have been made to utilize various actuating media to bias the sealing means into an optimum sealing arrangement, and while recognized as a possible actuating force, thermal means have never attained any substantial acceptance because of the great difficulty in effecting a practical arrangement for transforming a thermal change into an actuating force of a magnitude sufficient to move the sealing means towards or away from a cooperating sealing surface.

The chief object of this invention therefore is to provide an arrangement of sealing means that moves to accommodate a shifting in the sealing relationship between a rotor and its surrounding housing.

A further object of the invention is to utilize as the actuating force for an adjustable sealing means the same thermal force that causes the initial distortion of the rotor.

This invention therefore provides for a specific arrange-

2

ment that uses an available change of temperature in a rotary regenerative heat exchanger to maintain sealing means in a predetermined sealing relationship throughout a wide range of temperature variation.

These and other objects of my invention will become more readily apparent when read in conjunction with the drawing in which:

FIGURE 1 is a sectional elevation of a rotary regenerative heat exchanger involving the invention, and

FIGURE 2 is an enlarged sectional elevation showing the upper and lower radial seals that comprise the invention.

In the drawings the numeral 10 designates a rotor having a cylindrical shell 12 divided into sector-shaped compartments by radial partitions 14 that are connected to a central rotor post 16 which is turned about its axis by means such as a motor and reduction gearing arrangement shown at 18. The rotor compartments contain a mass of heat absorbent material, usually in the form of spaced metallic plates, which first absorb heat from the heating fluid entering the heat exchanger through a duct 22 that is connected to a boiler or other source of heat. After passing over the heat absorbent material and transmitting heat thereto, the hot gases are discharged through an outlet duct 24 to which an induced draft fan (not illustrated) is usually attached. As the rotor turns slowly about its axis, the heated plates are moved into a stream of air or other fluid to be heated entering the heat exchanger through a duct 26 where the plates give up their heat to the air.

The rotor is rotatably mounted on a support bearing 28 in order that it may be rotated slowly about its axis by the motor and reducing gear arrangement. The rotor is supported for rotation within a cylindrical housing 34 that is provided at opposite ends with end or sector plates 36 which are apertured at circumferentially spaced locations 38 and 40 to admit and discharge the heating fluid and the fluid to be heated. In order that the fluid traversing the heat exchanger do not intermix, the end plates 40 have imperforate portions between apertures 38 and 40 that are at least as great in circumferential extent as one rotor compartment. Radial seals 44 which are mounted on the end edge of radial partitions 14 are adapted to rub against or in closely spaced relation with the confronting surface of the adjacent sector plate to effectively isolate a complete sectorial compartment between apertures and thus preclude the by-passing of the radial partitions. Other sealing means 46 known as circumferential seals extend around the end edge of the rotor to prevent fluid by-passing the rotor by flowing through the annular clearance space 48 between the rotor and housing.

In accordance with the present invention, the radial seals 44 comprise plane metallic leaves that are pivotally secured at their inner ends by a pivot pin 52 to an end edge of the radial partition while the opposite ends slidably abut a side of each partition and extend radially outward to a point adjacent the rotor shell 12. While the in-board end of each sealing means 44 is pivotally held to the radial partition one outboard end of each sealing means is therefore movable in an axial direction to permit movement toward or away from the confronting face of the adjacent end plate in accordance with the relative distortion of the rotor and the rotor housing. A thermal actuating bar 54 is positioned substantially parallel to each sealing leaf with its radial inner end secured to the rotor structure at a point 56 adjacent the pivot pin 52 in order that its outboard end may be free to expand or contract radially in accordance with normal variations in temperature. A bell-crank 58 is pivotally secured to the radial partition at a point intermediate the outboard ends of the radial seal 44 and the actuating bar 54 to permit linking one arm of the bell crank to the expansion

bar 54 while an angularly displaced arm of the bell crank is linked to the adjacent end of the sealing means 44.

The exact configuration of the bell crank 58 is not deemed critical inasmuch as the angular displacement or the relative length of its arms may be varied to best comply with existing conditions to provide a predetermined axial movement of the sealing means when the length of the expansion bar 54 is altered by a thermal variation. Similarly, an additional linkage means as illustrated by numeral 60 may be used at either end of the rotor when necessary to translate a radial movement of bar 54 to an axial movement of the adjacent seal 44.

To provide a suitable actuating force to the sealing means, the thermally responsive actuating bars 54 are necessarily formed of material having a coefficient of expansion different from that of the radial partitions to which they are secured. For the application illustrated in the drawing wherein the upper end of the rotor lies adjacent the inlet for the heating fluid or at the "hot" end of the rotor, the thermal expansion bars must have a coefficient of expansion greater than that of the radial partition to which they are attached in order that the seals will move upward when the rotor turns downward in response to a differential of expansion. With a reversal of flow conditions wherein the "hot" end of the rotor would lie at the opposite end, heating the rotor would cause it to "turn up" such that its upper edge would move toward its adjacent end plate while its lower end would move away from its adjacent end plate. Such conditions would require a reversal of the linkage arrangement to provide an opposite movement of the sealing means to compensate for the accompanying rotor distortion. Thus it is evident that such changes as may be required in the linkage arrangement can be made without departing from the spirit of the invention, and it is intended that all matter contained in the above description or shown in the accompanying drawings shall be interpreted as illustrative only and not in a limiting sense.

I claim:

1. Regenerative heat exchange apparatus having a rotor that includes a cylindrical rotor shell joined to a rotor post by radial partitions to form sectorial compartments that carry a mass of heat absorbent material, and a cylindrical housing surrounding the rotor provided at opposite ends thereof with end plates including imperforate portions located between circumferentially spaced apertures that direct the flow of heating fluid and fluid to be heated through the heat absorbent material carried by the rotor; radial sealing means bridging the space between an end edge of each radial partition and the

confronting face of an adjacent end plate adapted to preclude fluid flow therebetween, said sealing means comprising a leaf member laterally abutting an end edge of the radial partitions and having one end pivotally attached thereto to permit movement of a free end toward and away from the adjacent end plate; a bell crank pivotally attached to the radial partition adjacent the free end of the leaf member; thermal expansion means having one end affixed to said partition and an opposite end pivotally attached to an arm of said bell crank; and a pivotal linkage between a spaced arm of said bell crank and said free end of the leaf member arranged to transform radial movement of said thermal expansion means into an axial force moving the sealing leaf relative to its adjacent end plate.

2. Regenerative heat exchange apparatus having a rotor that includes a cylindrical rotor shell joined to a rotor post by radial partitions to form sectorial compartments that carry a mass of heat absorbent material, and a cylindrical housing surrounding the rotor provided at opposite ends thereof with end plates including imperforate portions located between circumferentially spaced apertures that direct the flow of heating fluid and fluid to be heated through the heat exchange material carried by the rotor, radial sealing means bridging the space between an end edge of each radial partition and the confronting face of an adjacent end plate to preclude fluid flow therebetween, said sealing means comprising a radial sealing leaf pivotally attached to the end edge of the radial partition lying adjacent the rotor post, a bell crank pivotally attached to the radial outboard end of each partition adjacent the corresponding end of said radial sealing leaf, thermal expansion means having its inboard end fixed to said radial partition adjacent the rotor post and its outboard end pivotally secured to an arm of the bell crank, and a pivoted linkage connecting a spaced arm of said bell crank and the outboard end of said radial sealing leaf whereby radial movement of said thermal expansion means moves the sealing means axially with respect to its adjacent end plate.
